Fales & Brown.

Device for Careening Ships.

Patented Mar. 9, 1833.

(14737) March 9, 1833
445
Letters Patent of James. Gates and
Thomas D'Broon, dated 9th March, 1833

The schedule referred to in these Letters Patent, and making
part of the same, containing a description in the words of
the said James Gates and Thomas D'Broon themselves of their
improvement in the machine for preventing accidents in
carrying or hauling down ships or vessels, called "a Safety
Chain".

Be it known that we James. Gates & Thomas D'Broon both of
New Bedford in the County of Bristol and Commonwealth of
Massachusetts Mechanics, have invented a method of preventing
accidents in the carrying, or hauling down ships or vessels for
the purpose of examining, repairing, or stopping, their bottoms
called "A Safety Chain" which is described as follows to wit:-

Whereas in the common mode of carrying ships for the
aforeaid purposes, serious accidents sometimes occur by too
great a strain upon the masts or shrouds of the vessel, we
propose to affix a chain to the top of the mast or masts by
which the vessel is hauled down, to expose her bottom, which
chain is to be connected with two nut & screw to other chains
to be fastened to the wale or sides of the vessel by lightning
the chain by means of the screw to relieve the strain on
the mast or shrouds of the vessel, occasioned by the force
applied to the opposite side of the mast of the vessel to face
her side out of water. The application of these chains
& screws may be better understood by reference to the drawing
annexed & made part of this specification.

In the Drawing Fig 14. M. is the mast of the vessel, A.
the portion of the chain affixed to the top of the mast B.B.
shackles connecting different parts of the chain, c.c.c.c.
different portions of the chain, M.M. nuts the which the screw
passes

116713
paper (Fig. D) being placed over the sides of the vessel & fastened
by a ring inside, to prevent the chain to the vessel, (Fig. B) plates
forming part of the bottom & applied to the vessel sides.

4. Bottom of the vessel to be drawn out & applied, (Fig. A) to
coats of the vessel. Fig. D represents a stopper of which
there are two to hold at each end to the chain on each side of
the nut, over which the screw passes in order to prevent the
screw from slipping or breaking, in case of too great strain
on it.

What we claim as our invention & wish to secure by
Letters Patent is the application of a Chain or Chains
of metal connected by a screw to the mast & sides of vessel
on the opposite side to that on which the force is applied
in order to carry them or haul their bottoms out of water
& thereby to prevent the accidents which ^{occur} in such operation,
when none or insufficient force counteracting force is
applied.
